UNITED STATES PATENT OFFICE.

LIONEL F. BOWERS, OF COLUMBIA, PENNSYLVANIA, ASSIGNOR TO COLUMBIA MANUFACTURING COMPANY, OF COLUMBIA, PENNSYLVANIA.

DRY-ROOM.

1,147,298.

Specification of Letters Patent. Patented July 20, 1915.

Application filed April 23, 1912. Serial No. 692,705.

To all whom it may concern:

Be it known that I, LIONEL F. BOWERS, a citizen of the United States, residing at Columbia, in the county of Lancaster and State 5 of Pennsylvania, have invented a new and useful Dry-Room, of which the following is a specification.

This invention relates to laundry drying rooms.

10 The primary object of the invention is to provide a drying room of that character in which the clothes are conveyed through the same by a trolley, with means for maintaining a continuous circulation of dry hot air.

15 A further object of the invention is to provide means for forcing the moisture which arises from the steam, which is used as a heating element, from the room or box.

A further object is to so dispose the radiators with respect to the baffle plates which 20 form the inner walls of the room that when the air in the drying compartment is forced downward that the same after reaching a point adjacent the floor of the room will 25 travel upward exteriorly of the drying compartment and around the vertically disposed radiators.

A still further object of this invention is to provide a conveyer supporting mechanism 30 which may be readily assembled and which may be conveniently disposed within the room or box.

Another object of the invention is to provide means for driving the conveyer in which 35 the driving element will discontinue the movement which transmits power to the conveyer in case of accidental stoppage of the apparatus, thereby preventing the breakage of the conveyer should the same be held 40 against movement by the stripping mechanism or other obstruction.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope 45 of what is claimed, without departing from the spirit of the invention.

In the drawings, Figure 1 is a longitudinal section. Fig. 2 a top plan view, a portion of the ceiling being broken away to show the 50 drying apparatus, and a portion of the hori-

zontally disposed radiators being broken away to show the arrangement of the fan and the conveyer tightening mechanism which latter mechanism is designed to impart longitudinal movement to one of the 60 sprockets which support the same, to compensate for the expansion and contraction of the conveying element. Fig. 3 is a top plan view illustrating the driving mechanism. Fig. 4 a transverse section taken on the line 65 4-4 of Fig. 2. Fig. 5 a transverse section taken through the trolley tightening mechanism, and Fig. 6 an elevation, partly in section, of the pinion and rack which control the movement of the bracket actuating rod. 70

In the drawings, 10 designates the outer casing which is preferably formed of wood and which is provided with a suitable metallic lining 11, spaced from the side walls 14 forming the air space 15. The front wall 16 75 of the box or cabinet is provided with suitable openings 17 through which the conveyer travels, and a centrally arranged door 19.

Disposed interiorly of the cabinet are four vertically extending beams 20, there being 80 two disposed at the front of the cabinet and two rearwardly of the same. Each pair of beams support a frame 21, the frame 21 being formed with extensions 22 angle irons 24 connecting the extensions 22 with the upper 85 terminals of the beams 20, the frame forming a support for the conveying mechanism and the baffle walls which will be hereinafter described, in detail. Disposed longitudinally 90 of the cabinet and adjacent the floor 25 there of are the manifold distributors 26, said distributors being arranged adjacent the walls of the cabinet, the distributors being connected by the transverse pipes 27 the rear-most pipe 27 being connected to a suitable 95 steam supply. Connected to the manifolds 26 and extending vertically and parallel with the side walls are the pipes 28 which constitute the radiators, these pipes are continued to a point adjacent the ceiling of the cabinet and are then conducted parallel with the ceiling to a point adjacent the center of the cabinet, the terminals of the pipes of each side being connected to a manifold 30, the manifolds at 100 their terminals being connected by pipes 31. It will be noted from this construction that 105 heat will be generated at the side walls and the ceiling of the cabinet. Baffle plates 32 are disposed parallel with the side and rear walls, said plates being formed of metal, and 110

terminating at a point above the floor. The plates are supported by the frame 21, the portions 33 of said frame which are disposed at an angle, supporting the angularly disposed portions 34 of the baffle plates, the baffle plates terminating short of the ceiling of the cabinet thus allowing a continuous circulation of air, means which will be hereinafter described, forcing the upper strata 5 of air down, displacing the lower strata which arise through the heating chamber, formed between the baffle plates and the side walls of the cabinet, the air rising again to the top of the cabinet.

10 The conveying mechanism consists of the U-shaped track 35 which may be disposed in any suitable course, consistent with the dimensions of the cabinet, the track being supported by the frame 21. The trolley is supported by the chain 36, the standards 15 which support the goods being connected to the chain, said standards being driven by the chain, their upper terminals being supported by rollers which ride in the channels of the U-shaped track 35. The chains 36 in the form illustrated in the drawings, pass about sprockets 37, 38, 39, 40 and 41, these sprockets being disposed in the usual manner within the cabinet, the shaft which 20 drives the sprocket 37, which transmits movement to the same being supported by the rearwardly disposed transverse beam 22. The portion of the track which extends beyond the cabinet is supported by the frame 25 40, the longitudinal bars 41 of which are secured to the beam or truss 21 being connected by the intersecting transversely extending bars 42, the terminals of the longitudinally disposed bar being formed with 30 apertured ears 43 which receive the outer terminals of truss rods or shrouds 44, the terminals 45 of which extend within ears 46 of lugs 47' which are secured to the cabinet. The many advantages of supporting 35 this portion of the conveyer which extends beyond the cabinet will be clearly apparent as it will be noted that this form of truss rod support may be readily disassembled when it is desired to ship the apparatus and 40 that the same may be readily secured in position when the apparatus is assembled.

45 The conveyer and the fans which will be hereinafter described, are driven by any suitable motor, the motor transmitting power 50 to the drive shaft 47, provided with pulleys 48 which drive the above mentioned fans. The shaft 47 is supported by brackets 49 and 50, a pulley 51 being disposed adjacent the bracket 50 the belt 52 which passes over 55 said pulley transmitting power through a suitable clutch control drive to the conveying mechanism. Interposed between the pulley 48 and the pulley 51 and supported by the shaft 47 is a friction clutch 54, this 60 clutch being of such construction that should

the conveying mechanism be temporarily stopped through contact of the clothes with the stripper, or other obstruction, the resistance thus offered to the conveyer will hold the belt 52, it being noted that when a pull 70 is directed on the belt 52, that the disk 55 will be held against movement, this construction forming a part of a separate application filed Apr. 23, 1912, Serial No. 697,751.

75 The many advantages of this construction will be clearly apparent as it will be noted that the operation of the conveyer will immediately cease as soon as the same is stopped in any manner, by meeting with an obstruction or by the hand of the operator 80 placing the goods upon the hangers. The belt 52 transmits movement to the pulley 57, which is loose on the shaft 59, the gear 60 being also driven by said pulley. This gear 60 drives a gear 61 mounted upon the 85 counter shaft 62. A sleeve 63 is loosely mounted upon this counter shaft, said sleeve being provided with a clutch face 64. The clutch 65 is splined upon the shaft 62 and is arranged to lock the sleeve 63 to the counter 90 shaft. Arranged upon this sleeve is a gear 66 which meshes with a gear 67 mounted upon the sleeve 68 which is loosely mounted on the shaft 59. A beveled pinion 69 is mounted upon this sleeve, said pinion meshing with the bevel gear 70 which drives the shaft 71 on which the sprocket 37 is mounted, which drives the conveying mechanism. It will be noted by this construction that the movement of the conveyer may be readily 95 controlled by the lever 64' which is disposed at a point adjacent the front of the cabinet and which is actuated by pull rods 65', the shaft 66' being rotated to throw the clutch 65 into and out of engagement with the clutch face 64 of the sleeve 63 which is 100 loosely mounted upon the shaft 62, this construction forming a part of a separate application, filed Apr. 25, 1912, Serial No. 692,706.

105 110 Fan shafts 66' and 67' are disposed within bearings 68' and 69' which are supported by the ceiling of the cabinet, said fan shafts being disposed at the transverse center of the ceiling, the fans being of a diameter 115 consistent with the width of the cabinet. These shafts 66' and 67' are supported by brackets 70' and 71', the shaft 66' being provided with a pulley 72 disposed within the bracket to support said shaft, a pulley 73 120 being similarly disposed within the bracket which supports the shaft 67', there being a second pulley 73' disposed on said shaft, a belt 74 driving the pulley 73' which is disposed on the terminal of the shaft 67 which 125 extends beyond the bracket 71, the belt 74 passing over the pulley 75 which is mounted upon the shaft 76 which is driven by the belt 77 which passes over the pulley 48, the shaft 77 being supported by brackets 78 and 130

79 which are secured to the ceiling of the cabinet. The pulleys 72 and 73 which are disposed within the bracket and secured to the shafts which drive the fans, are connected by the belt 80, the fan shafts in this manner being driven from the main drive shaft 47.

A baffle plate 81 is disposed transversely of the cabinet between the fans 82 and 83. 10 This baffle plate 81 is V-shaped in cross section and adjacent its terminals the same is formed with offsets 84 which are secured to the angularly disposed portions of the baffle walls. It will be noted, by this construction, 15 that the blast of the fans 82 and 83 will be directed toward the bottom of the cabinet, the fans forcing the air beneath the baffle walls and through the heating chamber formed between said walls and the side and 20 rear walls of the cabinet. Attention is called to the fact that the fans will not only direct the air between these walls, but that the same will force the moisture from the air through the opening in the front of the 25 cabinet through which the conveyer passes, thus maintaining within the cabinet a constant free circulation of dry air. Disposed beneath each of the fans are cups 85 and 86 which prevent the fans from creating a suction, which would tend to draw the air upwardly.

Attention is called to the fact that the entire structure is such as may be readily set up, and the various parts be quickly disseminated, for shipment. Attention is also called to the fact that this drying apparatus provides means for maintaining a constant circulation of air from which the moisture is removed, the air being highly heated, as it 35 passes between the baffle walls and the wall of the cabinet, being again heated by the longitudinally disposed radiators as it passes over said baffle walls and before it contacts with the clothes.

40 The sprocket wheel 39 around which the conveyer passes adjacent the front of the cabinet is supported by the bracket 86 which embraces said wheel and is provided with the extension 87' which supports the rod 88 in any suitable manner. The bracket 86 is supported for a sliding movement by a U-beam 92 which is supported by a bracket 89 which is secured to a forward transverse beam 21, a slot 90 being formed in the beam 55 92 to permit the same to move freely with respect to the said beam. The U-beam 92 is disposed longitudinally and centrally of the cabinet, the bracket 86 being formed with an extension 93 which supports rollers 94 which 60 ride on said U-beam.

It will thus be noted that when the rod 88 is moved forward, it will tighten the chain on which the clothes supports 36^a are mounted. The rod extends to a point adjacent the rear of the cabinet and passes

through a hanger 94' which is secured to the U-beam 92, the hanger 94' supporting the transversely disposed shaft 95 on which the pinion 96 is positioned, the shaft 95 extending beyond the bracket, a drum 97 being disposed on said shaft, a cable 98 passing over said drum, said cable carrying a weight 99 which has a tendency to revolve the drum 97, this movement of the drum causing the shaft 95 to rotate the rotation of the shaft 70 75 95 thrusting the rod 88 forward, the pinion 96 engaging the rack 100 on the rod 88, the forward thrust of the rod 88 causing a forward movement of the sprocket 39. In a drying apparatus of this character the 80 sprocket chain expands and contracts and it will be noted from the foregoing that as the chain expands the constant forward thrust of the rod 88 will always maintain the same in proper contact with the sprockets. The 85 many advantages of this construction will be clearly apparent as it will be noted that the same forms an effective chain tightener which will at all times retain the chain in proper relation with the sprockets. 90

What is claimed is:—

1. In a drying apparatus, a cabinet, radiators disposed parallel with the side walls and top wall of the cabinet, baffle walls supported between the top and wall and floor of 95 the cabinet, said radiators being disposed between the baffle walls and the side walls of the cabinet, and a conveyer disposed to travel between said baffle plates.

2. In a drying apparatus, a cabinet, a support disposed within the cabinet, baffle walls spaced from the walls of the cabinet, said walls being carried by said support, the upper and lower edges of the baffle walls being spaced from the top and bottom walls of 100 the cabinet, said upper edges being disposed at an angle, a conveying mechanism disposed for travel between said baffle walls, radiators disposed between said baffle walls and the walls of the cabinet, said radiators 105 extending parallel with the top wall of the cabinet, and a plurality of fans for forcing the air at the top of the cabinet through the space inclosed by the baffle walls to the space between the baffle walls and the walls of the 110 cabinet.

3. In a drying apparatus, a cabinet, a support disposed within the cabinet, baffle walls spaced from the walls of the cabinet, said walls being carried by said support, the upper and lower walls of the cabinet being spaced from the top and bottom walls of the cabinet, said upper edges being disposed at an angle, a conveying mechanism disposed 120 for travel between said baffle walls, radiators disposed between said baffle walls and the wall of the cabinet, said radiators extending parallel with the top wall of the cabinet, a plurality of fans for forcing the air at the top of the cabinet through the space inclosed 125 130

by the baffle walls to the space between the baffle walls and the walls of the cabinet, and a baffle plate disposed between the fans.

4. In a drying apparatus, a cabinet, a support disposed within the cabinet, baffle walls spaced from the walls of the cabinet, said walls being carried by said support, the upper and lower walls of the cabinet being spaced from the top and bottom walls of the cabinet, said upper edges being disposed at an angle, a conveying mechanism disposed for travel between said baffle walls and the wall of the cabinet, radiators extending parallel with the top wall of the cabinet, a plurality of fans for forcing the air at the top of the cabinet through the space inclosed by the baffle walls to the space between the baffle walls and the walls of the cabinet, and a V-shaped baffle plate disposed transversely of the cabinet and arranged between the fans.

5. In a drying apparatus, a cabinet, a frame disposed within the cabinet, baffle walls supported by the frame, said walls being spaced from the walls of the cabinet with the upper and lower edges of said walls being spaced from the bottom and top walls of the cabinet, the upper edges of said baffle walls being disposed inwardly at an angle, angular supports for said baffle walls, a conveyer disposed for movement between said baffle walls, sprockets supporting said conveyer, a bracket supporting one of said sprockets, a beam disposed longitudinally of the cabinet, a beam forming a support for said bracket, said bracket being mounted to move with respect to said beam, a rod secured to said bracket, a bracket supported

by the beam, a pinion mounted on said shaft, a rack carried by the rod and arranged to mesh with said pinion and weighted means actuating said shaft to impart a forward thrust to said rod.

6. In a drying apparatus, a cabinet, baffle plates disposed within the cabinet and spaced from the walls of the same, means for heating the air between the baffle plates and the side walls of the cabinet, a V-shaped baffle plate disposed transversely of the cabinet adjacent the top thereof and a fan disposed upon each side of said transversely disposed plate.

7. In a drying apparatus, a cabinet, radiators disposed adjacent the side and ceiling of the same, vertically disposed baffle plates and fans disposed to force heated air from the space between the baffle plates to the space between the baffle plates and the side walls of the cabinet.

8. In a drying apparatus, a cabinet, baffle plates disposed within the cabinet and spaced from the walls of the same, means for heating the air between the baffle plates and the side walls of the cabinet, a baffle plate disposed transversely of the cabinet adjacent the top thereof and a fan disposed upon each side of said transversely disposed plate.

In testimony that I claim the foregoing as my own, I have hereto affixed my signature in the presence of two witnesses.

LIONEL F. BOWERS.
